203,792

CIGAR HOLDER OR THE LIKE

Edith Adams Mills, 2301 Bowmont Drive,
Beverly Hills, Calif.

Filed July 6, 1965, Ser. No. 86,051

Term of patent 14 years

(Cl. D85—8)

FIGURE 1 is a perspective view of a cigar holder or the like embodying my new design;

I claim:

The ornamental design for a cigar holder or the like, as shown.
